CLAIM

The ornamental design for a razor handle, as shown and described.

DESCRIPTION

FIG. 1 is a perspective view as seen from the front side of a section of a razor handle having an end portion in accordance with the present invention;

FIG. 2 is a front view of the razor handle of FIG. 1;

FIG. 3 is a back view of the razor handle of FIG. 1;

FIG. 4 is a left side view of the razor handle of FIG. 1;

FIG. 5 is a right side view of the razor handle of FIG. 1;

FIG. 6 is a top view of the razor handle of FIG. 1; and,

FIG. 7 is a bottom view of the razor handle of FIG. 1.

The broken lines connecting the outer solid lines of the of the razor handle represent the bounds of the claim. The remaining broken lines illustrate portions of the article. None of the broken lines forms part of the claimed design.
